UNITED STATES PATENT OFFICE.

WILLARD F. RICHARDS, OF DEPEW, NEW YORK, ASSIGNOR TO GOULD COUPLER COMPANY, OF NEW YORK, N. Y.

CAR-COUPLING.

1,082,822.

Specification of Letters Patent. Patented Dec. 30, 1913.

Application filed February 27, 1911. Serial No. 611,025.

To all whom it may concern:

Be it known that I, WILLARD F. RICHARDS, a citizen of the United States, residing at Depew, in the county of Erie and State of New York, have invented a new and useful Improvement in Car-Couplers, of which the following is a specification.

This invention relates more particularly to railway car couplers of the Master Car Builders' type in which a vertically-movable lock is employed for the horizontally-swinging knuckle.

The objects of the invention are to produce a strong, durable and thoroughly serviceable and practical car coupler which will fulfil the demands of the railways, which complies with all of the requirements of the Master Car Builders' Association, is of simple construction, and can be manufactured economically and with the minimum amount of labor; also to provide a coupler with a vertically-movable lock capable of being operated by the ordinary top operating devices located above the coupler and having a bottom operating attachment for the lock which can be removed when it is desired to use the coupler on a car equipped with such top operating means, whereby the coupler can be quickly and easily converted from a bottom-operated to a top-operated coupler.

In the accompanying drawings, consisting of two sheets: Figure 1 is a longitudinal sectional elevation of a car coupler embodying the invention, showing the locked position of the parts. Fig. 2 is a similar view, showing the lock lifted and the knuckle released. Fig. 3 is a transverse sectional elevation thereof in line 3-3, Fig. 4 showing the coupler in lock set position. Fig. 4 is a sectional plan thereof in line 4-4, Fig. 3. Fig. 5 is a longitudinal sectional elevation thereof, on a reduced scale, showing the lock provided with a link for operating it from above.

Like reference characters refer to like parts in the several figures.

A represents the coupler head, B the horizontally-swinging knuckle, and C the knuckle lock. The knuckle, as usual, is pivoted at one side of the head and is provided with a tail b which extends rearwardly into the head and preferably has a tail-extension b' which projects laterally through a hole b² in the adjacent side wall of the head when

the knuckle is closed. Preferably the lock C is arranged in the rear central portion of the coupler head to slide vertically into and out of locking position between the inner end of the knuckle tail and the side wall c of the head, and consists of a block or body of substantially cube-shape and a vertical guide stem c' which projects downwardly from the body through a hole c² in the bottom of the head. Vertical guide ribs c³ and c⁴ are provided on the upper portions of the front and rear walls respectively of the head, and these ribs, together with the front and rear walls and the side wall c of the head, form a guide pocket or cavity for the lock in the upper portion of the head. When the lock is in its lower, or locking, position, the upper portion of the lock body extends up into this guide pocket, as shown in Fig. 1, so that the pocket cooperates with the guide stem c' to retain the lock in an upright position and guide it vertically. The stem c' is made separate from the lock body and is detachably secured thereto in any suitable way, for instance, as shown in Figs. 1-3, the stem is made with an integral tapered, round thread which is screwed into a threaded socket in the lock body, and with a head c⁵ of square or other shape adapted to be engaged by a suitable tool for screwing the stem into the lock body. The lock body is inserted into the coupler head through the knuckle opening in the front wall thereof and the guide stem is then inserted through a hole d in the top of the head and screwed into the lock body by the tool, which is also inserted through the hole d.

As the lock body bears directly against the front and side walls of the coupler head opposite to the point at which the knuckle tail engages the lock, the guide stem c' is relieved from the draft strains on the knuckle, so that a slender stem can be used and consequently the hole c² in the bottom of the head does not have to be made large enough to appreciably weaken the head. The described construction also permits the use of a small hole d in the top of the head, and as the lock does not extend into the hole d in the top of the head it will not bind or stick and work hard in the event that the top of the coupler head is distorted out of its original shape or position by the severe shocks and blows to which the coupler is subjected in service, as might happen with a

lock having rigid parts extending through holes in the top and bottom of the head.

The hole *d* in the top of the head is preferably closed by a suitable cover or plug *D* which can be removably secured in the hole in any usual or suitable way.

A bottom operating attachment for the lock is removably secured on the coupler head. This attachment, in the construction 10 shown, comprises a bearing bracket *E* which is detachably secured to and depends from the underside of the head, and a lever *F* which is pivoted on the bracket with its free end arranged beneath and adapted to engage the projecting lower end of the stem *c'* for lifting the lock. The free end of the lever has a cam face which engages the lower end of the lock stem. The coupler head is preferably provided with a holding 15 socket for the bearing bracket *E* formed by two parallel flanges *e* which depend from the underside of the head at opposite sides of the hole *c'* for the lock stem *c'* and a hook-shaped lug *e'* connecting the flanges *e* 20 in front of the hole *c'*. The upper end of the bearing bracket *E* is placed between the flanges *e* with its hook-shaped front end interlocked with the hooked lug *e'*, and is secured by a bolt or pin *e''* passing through 25 registering holes in the flanges *e* and the bracket. The bracket is thus rigidly and securely attached to the coupler by means of a single bolt and can therefore be quickly and easily secured to and removed from the 30 coupler together with the operating lever carried thereby. The bracket has parallel spaced legs between which the lock-operating lever *F* is located, and the lever has a cross shaft *f* formed integrally therewith, 35 which is journaled in bearing holes formed in the ends of said legs. The lever shaft *f* is provided at its ends with eyes *f'* in either of which a horizontal operating rod or shaft *f''*, which extends to the side of the car, is 40 adapted to be hooked.

f'' represents stop lugs on the sides of the legs of the bracket *E*, adapted to be engaged by the eyes *f'* of the lever shaft for limiting the downward swing of the outer 45 end of the lever *F*.

When it is desired to use the coupler on a car equipped with an operating shaft or device which is located above the coupler, the bottom-attachment, consisting of the bracket *E* and the connected lever *F*, is detached from the coupler. The cover *D* for the hole *d* in the top of the coupler head is also removed and the guide stem *c'* is preferably disconnected from the lock body 50 and is replaced by another guide stem *G*, shown in Fig. 5, which has a lifting link *g* connected to its upper end. This link extends up through the hole *d* in the top of the head and is adapted to be connected in 55 any usual or suitable way to the operating

shaft or device located above the coupler. If desired, a lock stem can be used, having means at its top, such as the eye on the stem *G*, to which the lifting link can be connected without removing the stem from the lock. 70 As it is only necessary to remove one bolt to detach the bottom operating attachment, the coupler can be quickly and easily converted into a top-operated coupler, and when so changed there is no projecting bracket 75 or part left on the bottom of the coupler head.

The coupler is preferably provided, as shown, with a lock-set or device for holding the lock in the knuckle releasing position, 80 and also with a knuckle-opening device actuated by the lock.

H represents the lock-set, which, as shown, is pivoted near one end in a slot in the lower end of the lock body. When the lock is lifted to unlock the knuckle, the lock-set will swing by gravity into the position shown in Fig. 3, in which one end thereof projects into a hole *h* in the side wall *c* of the head and rests on the lower edge of the hole, thereby holding the lock up above the knuckle tail in position to permit the knuckle to be swung open. When the knuckle is swung open its tail will strike the lower cam-shaped edge of the lock-set, 90 which depends below the body of the lock, thus disengaging the lock-set from the hole *h* and permitting the lock to rest on the tail of the knuckle. The tail-extension of the knuckle lies beneath and supports the lock 95 when the knuckle is fully opened. When the knuckle is again closed the tail is moved from beneath the lock and the lock will drop by gravity between the tail and the side wall *c* of the head and lock the knuckle. 100

I represents the knuckle-opening lever. Preferably an angle lever is employed which is pivoted between its ends on a pin *i* in the upper portion of the coupler head at one side of the lock. One arm *i'* of the lever 110 extends downwardly in rear of, or to one side of, the knuckle tail, and the other arm *i''* of the lever extends laterally with its end above and in position to be struck by a lug or part *i'''* on the lock. If the lock is moved to the limit of its upward movement when the coupler is not in connection with another coupler, the lug *i'''* will strike and swing the lever *I* on its pivot, which will throw the knuckle open. The pivot pin *i* for the 120 knuckle-opening lever is preferably driven into the hub of the lever through the bearing hole *i* for the pin in the rear wall of the coupler head and does not require any securing device. 125

Lock-set and knuckle-opening devices of other constructions could be employed.

I claim as my invention:

1. In a car coupler, the combination with a coupler head provided with a hole in its 130

bottom, and a horizontally - swinging knuckle, of a lock for the knuckle provided with a stem which projects downwardly through said hole, and a bottom-operating attachment for the lock comprising a bearing bracket and a movable operating device which is mounted on said bracket and is adapted to move said lock stem to lift the lock out of locking position, a part on the bottom of the head adapted to interlock with said bracket, and means for securing said bracket to said part, said bracket being detachable with said operating device from the coupler head, substantially as set forth.

2. In a car coupler, the combination of a coupler head provided with a hole in its bottom and with bracket securing means on its underside, a horizontally-swinging knuckle, a lock for the knuckle provided with a stem which projects downwardly through said hole, a bottom-operating attachment for the lock comprising a bearing bracket which detachably interlocks with said securing means on the under side of the coupler head, a lever which is mounted on said bracket and is adapted to engage said lock stem for lifting said lock out of locking position, and a fas-

tening device for detachably fastening said bracket to said securing means, substantially as set forth.

3. In a car coupler, the combination with a coupler head provided with a hole in its bottom and with parts on its bottom for the interlocking engagement of a bracket, a horizontally-swinging knuckle, a vertically-movable lock for the knuckle provided with a guide stem which projects downwardly through said hole, guiding means in the coupler head which coöperate with said guide stem to hold said lock in an upright position and guide it vertically, and a bottom-operating attachment for the lock comprising a bearing bracket which is detachably secured to said parts on the coupler head, and a lever which is pivoted on and removable with said bracket and is adapted to engage said lock stem for lifting the lock out of locking position, substantially as set forth.

Witness my hand, this 22nd day of February, 1911.

WILLARD F. RICHARDS.
